DESIGN FOR A HYDRAULIC SELECTOR VALVE

Ottmar A. Kehle, West Los Angeles, Calif., assignor to Adel Precision Products Corp., a corporation of California

Application August 5, 1943, Serial No. 110,841

Term of patent 14 years

(Cl. D78—1)

To all whom it may concern:

Be it known, that I, Ottmar A. Kehle, a citizen of the United States and residing at West Los Angeles, in the county of Los Angeles, State of California, have invented a new, original, and ornamental Design for a Hydraulic Selector Valve, of which the following is a specification, reference being had to the accompanying drawing, forming part thereof, in which:

Fig. 1 is a perspective view of a hydraulic selector valve showing my new design;

Fig. 2 is a perspective view of the valve looking at the reverse side and end from that shown in Fig. 1;

Fig. 3 is an end elevation of the valve looking toward the end shown in Fig. 1, on a slightly reduced scale.

I claim:

The ornamental design for a hydraulic selector valve, substantially as shown.

OTTMAR A. KEHLE.
